John B. Leifert

UNITED STATES PATENT OFFICE.

JOSEPH E. KENNEDY, OF NEW YORK, N. Y.

JAW CRUSHER.

Application filed February 20, 1928. Serial No. 255,819.

This invention relates to jaw crushers for crushing rock, ore and the like and particularly to means for mounting the movable or swinging jaw member of the crusher to a supporting frame.

In crushers of this character the swinging jaw member is of a hollow reinforced frame structure arranged on one face with a crushing jaw facing a fixed jaw member. The 10 swinging crushing member is pivotally mounted in the frame of the crusher, as disclosed by my prior Letters Patent #1,446,753, dated February 17, 1923, by pivot pins or studs mounted in recesses in the frame to extend from opposite sides and adjacent the top 15 of the crushing member. The pivot studs are held against rotation in said recesses by being forcibly engaged in the recesses keyed to the frame to rotatably support the frame in bearings carried by the crusher. Due to the weight 20 of the jaw and the great stresses and strains exerted thereon in operation of crushing in spite of the keying of the frame to the pivot studs they become loose allowing movement 25 of the crushing member and pivot studs not only resulting in the inefficient operation of the crushing member but invariably resulting in the fracturing of the crushing member should the play between a pivot and the frame 30 not be taken up promptly. This requires the removal of the crushing member from the crusher frame, which is a tedious job.

It is the principal object of the invention to overcome these disadvantages by constructing 35 the pivot supports integral with the jaw frame and arranged in such a manner as to increase the strength thereof.

Other objects and advantages will herein-after appear.

In the drawing accompanying and forming 40 a part of this application, Figure 1 is a cross sectional view of the crushing member showing the same mounted in a crusher frame, only so much of the frame being shown as is essential to an understanding of the invention; and

Figure 2 is a cross sectional view of the 45 crusher taken on line 2—2 of Figure 1 looking in the direction of the arrows, showing my improved crushing member, partly in section mounted therein.

Like references designate like parts throughout the specification and drawing.

In carrying out the invention there is provided a supporting frame 3, only part of 50 which is shown, as it is similar to that shown

in the aforementioned Letters Patent, with one end member thereof inclined and adapted to releasably carry a plate jaw 4 of wear resisting material forming the fixed jaw of the 60 crusher. In opposed relation to said fixed jaw, a crushing member is swinging or pivotally mounted in the side members of the supporting frame adapted to be oscillated by a pitman 5 eccentrically mounted on a drive 65 shaft 6 driven from a suitable source of power by a belt (not shown) passing around a fly wheel 7 fixed to the shaft 6 and flexibly connected to the crushing member by means of a toggle 8 in the form of a plate pivotally 70 mounted at opposite circular shaped edges thereof, as at 9, in bearings carried by the pitman and crushing member. The toggle is maintained in engagement in the bearings by means of rods 10 pivotally connected at one 75 end thereof to ears 11 extending from the bottom of the crushing member and slidably mounted at the opposite end in the other end member of the frame (not shown) arranged with a spring coiled about the rods at the latter end thereof, to compensate for the oscillation of the swinging crushing member.

The crushing member embodies a jaw carrying frame 12 of a hollow reinforced steel cast frame having one surface thereof recessed for the releasable engagement of a plate jaw 13 of wear resisting material arranged at the bottom edge with a recess of V-shape to engage a correspondingly V-shaped projection of the frame 12, as at 14, 85 and the upper edge of the jaw is arranged with a similar V recess engaging a V projection of a locking strip 15 having horizontally aligned perforations to carry bolts 16 adapted to pass through perforations in the frame 12 90 and secured thereto by nuts threaded on the ends of the bolts projecting beyond the rear of the jaw frame. The frame 12 is swingingly mounted in the frame 3 by laterally projecting trunnions 17, 18, cast integrally 100 with the frame and extending coaxially of a tubular portion 19 extending transversely of one end of the frame with the bore varying in diameter, as at 20, to reduce the cost of manufacture and the weight of the casting but providing a greater amount of material by having the bore of smaller diameter at the juncture of the trunnions and the body portion of the frame to serve as a reinforcement 105 and prevent breakage. The trunnions are machined to rotate in bearings in the frame 3 formed by shaping a portion of the frame 110

into a seat 21 and providing caps 22 for superposed engagement relative to the seats, comprising an arch portion and lateral extending flanges which are bolted to the frame. 5 The seats and caps are lined with a bearing material 23. The tubular portion of the frame 12 is arranged with spaced eyes cast integral therewith for the engagement of tackle means to facilitate the handling of the 10 frame 12 to mount the same in the bearings 21 of the supporting frame 3.

Having thus described my invention I claim:

1. A jaw for jaw crushers, comprising a 15 rectangular member having an integral tubular portion extending along a marginal portion thereof with the ends of said tubular portion extending beyond the opposite sides of the rectangular member to constitute trunnions for supporting the jaw in the crusher 20 frame.

2. A crushing member for jaw crushers, comprising a rectangular jaw carrying frame arranged with integral trunnions extended from opposite sides of the frame at a marginal portion thereof to pivotally mount the frame in the crusher frame, and said jaw carrying frame having one face recessed and arranged for mounting a crushing jaw therein. 25

3. A crushing member for jaw crushers as 30 claimed in claim 2, wherein the trunnions comprise the ends of a tubular portion at a marginal portion of the frame extended from opposite sides of the frame, and the bore in 35 said extended ends of the tubular portion being of less diameter than the intermediate portion to reinforce the same.

Signed at the city of New York, in the county of New York and State of New York 40 this 2nd day of February 1928.

JOSEPH E. KENNEDY.
